SUPPORT OR REST

Filed Dec. 17, 1921

2 Sheets-Sheet 2

UNITED STATES PATENT OFFICE

JOSEPH EIFEL, OF CHICAGO, ILLINOIS

SUPPORT OR REST

Application filed December 17, 1921. Serial No. 523,083.

My present invention relates broadly to supports or rests more particularly to devices of the character referred to adapted for use with hinged elements and has special reference to the provision of an improved variable rest peculiarly available for service in connection with a cover such as that of a relatively large and heavy loose leaf holder.

Among the more important objects of my present invention are the provision of an improved form of rest adapted to be moved out of the way when not in use, and more particularly, one adapted to be folded against the cover and preferably within the outline thereof; the provision of a variable rest for a cover adapted to sustain the cover in different predetermined positions; the provision of a rest for a cover which will in use not only not interfere with the movement of the article covered but on the contrary will facilitate movement thereof; together with such further and additional objects as may herein-after be pointed out or become manifest.

In attaining the objects suggested, together with certain incidental benefits and advantages which will below appear, I have provided certain constructions illustrated in the accompanying drawings, wherein—

Figure 1 is an end view partly broken away illustrating a loose leaf holder with certain supports or rests embodying my invention applied thereto;

Figure 1^a is a transverse sectional view taken on the line 1^a—1^a of Figure 1, looking in the direction indicated by the arrows;

Figure 2 is a side elevation of a portion of a cover showing a modified form of the support in a completely closed or nested position;

Figure 3 is a section taken on the line 3—3 of Figure 2;

Figure 4 is a view similar to that of Figure 2 showing the support, however, in an opened position; and

Figure 5 is a fragmentary view, in horizontal section, showing the support in a partly open position.

In Figure 1 of the drawings, I have shown, for purposes of illustration, my present invention embodied in connection with the covers 10, 10 of a loose leaf ledger, 11, of a type

adapted for so-called "machine bookkeeping".

These covers, 10, are conveniently provided with depressions or pockets, 12, preferably lined with metal, as indicated at 13, secured in position in any desired manner as by the screws 14 to form a housing.

Pivoted within the pocket, 12, by means of the pins, 15, is the support assembly, indicated generally at 16. This assembly is mounted to swing about an axis parallel to the cover, 10, and preferably at a right angle to the hinge, 17, of the cover.

As shown toward the left of Figure 1, the assembly, 16, comprises the member, 18, pivoted directly to the cover by means of the pins, 15, and the member, 19, pivoted to the member 18 at the point 20 and arranged for movement in a plane parallel thereto, and preferably so dimensioned as to be positioned within the outline of the member 18. In short, the member 19 serves in effect as an extension of the member 18.

For holding this extension, 19, in any one of a number of predetermined desired positions, the outer edge 21 of the member 19 is preferably made substantially concentric with its axis of rotation about the pivot 20 and is preferably provided with notches, 22, disposed to be engaged by the pawl, 23, pivoted to the member 18 at the point 24 and maintained in operative position by the spring 25 passing over the pin 26 and under the pin 27.

In the utilization of the form of rest just described, the assembly 16, which in its normal position is within the pocket, 12, and within the general outline of the cover, 10, is swung to the position indicated at the left of Figure 1 and then the extension 19 is moved outwardly as shown and adjusted into position to support the cover 10 at the desired angle. The pawl, 23, acting automatically prevents any reverse or closing movement of the extension 19.

To the end that the movement of the book 19 may not be interfered with, I have mounted at 28 an anti-friction roller 29 the axis of rotation of which is so positioned that the book may be moved laterally in either direction with the greatest of facility.

When it is desired to retract the extension 100

19, the end 30 of the pawl 24 is depressed and to permit this the member 18 has been cut away as indicated at 31.

Inasmuch as it may be desirable at times to have the support at variable distance from the edge of the cover 10, I have provided the modified embodiment shown at the right of Figure 1 wherein the assembly 16^a instead of being pivoted directly upon the pins 15 is mounted for relative sliding movement with reference 10 to the member 35 which in turn is mounted directly upon the pivot pins 15. As will be observed from an inspection of Figure 1^a, the member 35 may be provided with a right-angularly shaped channel 35^a, which receives 15 the complementally shaped flange 35^b formed upon the inner plate of the assembly 16^a, the snug engagement between the channel 35^a and flange 35^b serving to frictionally hold the assembly 16^a and member 35 in 20 positions of adjustment while permitting their relative movement. Of course, the structure shown in Figure 3 may be resorted to for use in the assembly 16^a, if practicable.

25 In the embodiment of my invention illustrated in Figures 2 to 5, I have made provision for the sliding referred to above by employing the construction now to be described.

Viewing Figure 3, the member 36 is pivoted by means of the pins 15 in the pocket 30 12, said member 36 being reduced in width as indicated at 37 and still further reduced in thickness to form a neck intermediate its ends by means of the grooves indicated at 35 38. The element 18^b of the assembly comprises the parallel walls 39, 39 the edges of which are turned inwardly as indicated at 40 to slidably engage in the grooves 38.

For maintaining the assembly 16^b in either 40 open or closed position, I provide the inner widest portion of the member 36 with the flat surfaces 41 and a squared corner 42 which coact with the strap spring 43 cut away from metal lining 13 of the assembly housing member, as clearly shown in Figure 5.

Having thus described my invention and illustrated its use, what I claim as new and desire to secure by Letters Patent is—

1. In a device of the character described, 50 in combination, a pivoted book cover member, means for supporting said member in partly open position, including a plurality of movable elements relatively displaceable about one axis and jointly displaceable about an axis at an angle to the first-mentioned axis.

2. In a device of the character described, 60 in combination, a pivoted book cover member, means for supporting said member in partly open position, including a plurality of movable elements relatively displaceable about one axis for varying the dimensions of said support, and jointly displaceable about an axis at an angle to the first-mentioned axis.

65 3. In a device of the character described,

in combination, a book cover member and means for supporting said member in partly open position comprising an anti-friction base-engaging member.

4. In a device of the character described, 70 a loose leaf holder having relatively movable side members and means for supporting said side members in partly open position including oppositely disposed anti-friction base-engaging members.

5. In a device of the character described, 75 a loose leaf holder having relatively movable side members and means for supporting said side members in partly open position including oppositely disposed anti-friction base-engaging members each including a roller.

6. In a device of the character described, 80 in combination, a book cover member and means for supporting said member partly open and slidably adjustably mounted thereon.

7. In a device of the character described, 85 in combination, a book cover member and means for supporting said member partly open and pivoted thereto and slidably mounted ed thereon.

8. In a device of the character described, 90 in combination, a book cover member and angularly variable means for supporting said member partly open and slidably mounted thereon.

9. In a device of the character described, 95 in combination, a hinged book cover member and means for supporting said member in partly open position, said means being variable in position both angularly and bodily.

10. In a device of the character described, 100 in combination, a book cover member and means for supporting said member in partly open position, said means being variable in position with reference both to the plane of the cover and to the edge of the cover.

11. In a device of the character described, 105 in combination, a pivoted book cover member and means for supporting said member in partly open position comprising means movable about axes at an angle to each other and means for holding said supporting means at predetermined angles about each of said axes.

12. In a device of the character described, 110 in combination, a pivoted book cover member and means for supporting said member in partly open position comprising means movable about axes at an angle to each other and independent means for holding said supporting means at predetermined angles about each of said axes, one thereof being carried by the cover and the other by the supporting means.

13. In a device of the character described, 115 in combination, a book cover member and means for supporting said member in a partly open position, said means being angularly 120

130

variable in different planes and being also bodily movable relatively to the cover.

14. In a device of the character described, in combination, a book cover member and means for supporting said cover member in partly open position movable on angularly related axes into and out of position to support said cover.

15. In a device of the character described, in combination, a book cover member having variable dimensions and means for supporting said cover member in partly open position movable on angularly related axes into and out of position to support said cover.

16. In a book cover support, in combination, a pivoted book cover member and means for supporting said member in partly open position comprising members respectively movable about axes at an angle to each other.

17. In a book cover support, in combination, a pivoted book cover member and means for supporting said member in partly open position comprising members respectively movable about a plurality of angularly related axes.

18. In a book cover support, in combination, a pivoted book cover member and means for supporting said member in partly open position comprising members respectively movable about relatively fixed axes at an angle to each other.

19. In a book cover support, in combination, a pivoted book cover member and means for supporting said member in partly open position comprising members respectively movable about a plurality of relatively fixed axes.

20. In a book cover support, in combination, a pivoted book cover member and means for supporting said member in partly open position comprising means movable about axes at an angle to each other, said means being removable from operative position to within the confines of said cover.

21. In a device of the character described, in combination, a book cover member, and means for supporting said cover member in various angular positions which is mounted within the outlines of the cover member, and movable in part outside the same.

22. In a device of the character described, in combination, a book cover member, and means for supporting said cover member in various angular positions which is mounted within the outlines of the cover member, and movable in part outside the same, said means for supporting including two relatively movable members, and means for holding said members in positions of relative adjustment.

23. In a device of the character described, in combination, a book cover member, and means for supporting said cover member in various angular positions which is mounted within the outlines of the cover member, and movable in part outside the same, said means

for supporting including two relatively movable members, and means for locking said members in predetermined intermediate or extreme positions of adjustment.

24. In a device of the character described, in combination, a book cover member, and means for supporting said cover member in various angular positions which is mounted within the outlines of the cover member, and movable in part outside the same, said means for supporting including two relatively movable members, one pivoted to the cover member and the other pivoted to said pivoted member on an axis at substantially right-angles to the pivot on said cover.

25. In a device of the character described, in combination, a book cover member, and means for supporting said cover member in various angular positions which is mounted within the confines of the cover member, and movable in part outside the same, and clamping means for automatically maintaining the parts of said supporting means in position to hold the cover partly open.

26. In a device of the character described, in combination, a book cover member, and means for supporting said cover member in various angular positions which is mounted within the confines of the cover member, and movable in part outside the same, and clamping means carried by the cover automatically maintaining the parts of said supporting means in position to hold the cover partly open.

27. In a device of the character described, in combination, a book cover member and means for supporting said member in partly open position, said means being mounted within the outlines of the cover and movable in part outside of the same and a portion of said means being further mounted for sliding movement when moved out of the outlines of said cover.

28. In a device of the character described, in combination, a book cover member and means for supporting said member in partly open position, said means being pivotally mounted within the outlines of the cover and movable in part outside of the same and a portion of said means being further mounted for sliding movement when moved out of the outlines of said cover.

29. In device of the character described, in combination, a book cover member and means for supporting said member in partly open position, said means being mounted within the outlines of the cover and being movable in part outside of the same both angularly and bodily with respect to said cover.

30. In a device of the character described, in combination, a pivoted book cover member, and means for supporting said member in partly open position including a device movable about a fixed axis parallel to said cover member and slidably relatively to said cover.

31. In a device of the character described, in combination, a book cover member and means for supporting said member in position which is mounted within the outlines of said cover member, and is movable in part outside of same, said means being extensible, and means for locking same in various positions of extension.
32. A device adapted for supporting the cover of a book, which includes a plurality of movable elements one of which is arranged for attachment to the cover, said movable elements being relatively displaceable about one axis and jointly displaceable about an axis at an angle to the first-mentioned axis.
33. A device adapted for supporting the cover of a book, which includes a plurality of movable elements one of which is arranged for attachment to the cover, said movable elements being relatively displaceable about one axis for varying the dimensions of the supporting device and jointly displaceable about an axis at an angle to the first-mentioned axis.

In testimony whereof I have hereunto
25 signed my name.

JOSEPH EIFEL.
